UNITED STATES PATENT OFFICE.

CHARLES E. MERRIFIELD, OF INDIANAPOLIS, INDIANA.

STRAW-STACKING MACHINE.

SPECIFICATION forming part of Letters Patent No. 268,514, dated December 5, 1882.

Application filed September 22, 1882. (No model.)

To all whom it may concern:

Be it known that I, CHARLES E. MERRIFIELD, a citizen of the United States, residing at Indianapolis, in the county of Marion and State of Indiana, have invented certain new and useful Improvements in Straw-Stacking Machines, of which the following is a specification.

My invention relates to improvements in straw-stacking machines which are operated from thrashing-machines; and the objects of my improvements are, first, to facilitate transportation; secondly, to simplify the operating of straw-stacker by belts and gearing, thus making a lighter-running machine. I attain these objects by the mechanism illustrated in the accompanying drawings, in which—

Figure 1 is a perspective view of the machine, with a sliding truck, on which is the straw-stacker, lowered when ready for transportation. Fig. 2 is a top view of the machine, showing the sliding truck raised into position when the machine is ready for operation, with the straw-stacker laid back in order to permit a full view of truck. Fig. 3 is a vertical longitudinal section on line $x x$, Fig. 2. Fig. 4 is a vertical transverse section on line $y y$, Fig. 3. Fig. 5 is a partial vertical transverse section on line $y y$, showing a similar but simpler combination. Fig. 6 is a section through head-block of derrick, showing method of securing spars in head-block, and the eyes for guy-ropes and pulley-block.

Similar letters refer to similar parts throughout the several views.

The carriage A has inclined rails $A' A'$, on which slides truck B, which is operated by windlass C and ropes $c c$, and is kept in place by guide-plates $b b$, secured to rails $B' B'$ of truck B. On truck B is fifth-wheel D and E, carrying straw-stacker K, which is supported by derrick T, and raised and lowered by windlass Q on cross-rail A^2 of carriage A, and a pulley-block hooked into eye p^2 of head-block P'. Said head-block is firmly secured to one of the spars P by bolts $p^3 p^3$. Spars are secured to rail A^2 by pins $a^2 a^2$, and kept in place until guy-ropes are fastened by pins $s s$ into shoulders S S, which are bolted to inclined rails $A' A'$. The guy-ropes are secured to head-block

into eye p' , thus making a derrick easily set up or taken down.

When the machine is to be transported the truck B, with straw-stacker K, is lowered by windlass C and ropes $c c$ to lower end of carriage A. The stacker is folded and laid on the upperend of carriage A, and the derrick T taken down and laid on the lower cross-bars of the carriage, thus making my machine less cumbersome and more easily handled than other machines in use.

In operation the belt f from thrashing-machine runs pulley F, with beveled gearing F' , which operates pulley H, to which is attached beveled gearing. Pulley H operates pulleys H' and H^2 by belt h . Pulleys H' and H^2 are connected by spindle g , and operate pulley H^3 , on which is a beveled gearing, by belt h' . Pulley H^3 operates beveled gearing G, which turns pulleys G' and I, by belting h^3 . Pulley I is attached to shaft J, which is supported by standards $e e$. Shaft J operates straw-stacker K. The spindle g , connecting pulleys H' and H^2 , operates in boxing R, which is rigidly bolted to stationary wheel D, and boxing R', secured to wheel F. Boxing R' is formed of two parts, and is held in position to boxing R by flanges r and r' . Flanges r and r' are formed upon boxings R and R' respectively. Flange r on boxing R fits over flange r' on boxing R' to secure it from displacement, while permitting the rotary motion of boxing R' in wheel E upon boxing R in wheel D. Straw-stacker K is pivoted to shaft J, and can be folded up for transportation.

Pulley F, with beveled gearing F' , and pulley H, with beveled gearing that operates pulleys H' and H^2 by belt h , can be dispensed with, and pulleys H' and H^2 can be operated, as shown on Fig. 5, by pulley-block F^2 , which is operated by belting f , and operates pulleys H' and H^2 by belting h .

What I claim, and desire to secure by Letters Patent, is—

1. The combination, in a straw-stacking machine, of carriage A, with inclined rails $A' A'$, windlass C, ropes $c c$, and sliding truck B with guide-plates $b b$, fifth-wheel D and E, spindle g , boxing R and R', and pulleys H' and H^2 , substantially as described.

2. The combination, in a straw-stacking machine, of belt f , pulley F, beveled gearings F' and H, belt h, pulleys H' and H², spindle g, boxing R and R', belt h', pulley H³, gear-wheel G, with pulley G', belt h³, with pulley I, standards e e, shaft J, and straw-stacker frame K, substantially as described, and for the purpose set forth.

3. The combination of spindle g, boxing R, and R', constructed with flanges r and r', and wheels D and E, for the purpose specified.

4. The combination, in a straw-stacking machine, of carriage A, derrick T, cross-rail A²,

pins a² a², windlass Q, shoulders S S, and pins s s, for the purpose specified.

5. The combination of spars P P, bolts p³ p³, and head-block P', formed with eyes p' and p², as specified, and for the purpose set forth.

In testimony whereof I have signed my name to this specification in the presence of two subscribing witnesses.

CHARLES E. MERRIFIELD.
